FLATWORK IRONER

Henry C. A. Meyer and Edgar R. Clark, Syracuse, N. Y., assignors to United States Hoffman Machinery Corporation, New York, N. Y., a corporation of Delaware

Application January 13, 1941, Serial No. 374,180

4 Claims. (Cl. 38—11)

This invention relates generally to improvements in laundry machines and particularly to improvements in flat work ironing machines. The ironing of fabrics has heretofore been generally done by having two cooperating ironing surfaces—one or both of which are heated—engage the material on opposite sides and applying direct mechanical ironing pressure to the material. An ironing machine designed for operation in this manner is disclosed in U. S. Patent 1,999,532, wherein there is provided a steam heated chest having a surface along which goods to be ironed may be continuously fed and ironed by means of an endless padded belt passing in close proximity to said surface, the required ironing pressure being attained by means for mechanically adjusting said belt with reference to the ironing surface of the chest. Such a machine suffers from certain inherent disadvantages such as eventual hardening of the padding of the belts and the difficulty of and the attention necessary in adjusting the elements to attain proper ironing pressure.

One of the objects of the present invention is to provide a simple and efficient flat work ironer of this general type with which padding is not needed, nor the employment of mechanical means for securing easily adjusted and uniformly distributed ironing pressure. These objects are accomplished by substituting for the usual padded belt, a belt composed of a very dense yet pliable and resilient heat resisting material, practically impervious to the passage of air, and employing therewith a specially constructed steam chest adapted to cooperate with suction means to establish uniformly distributed vacuum or sub-atmospheric pressure at the face of the steam chest, in such manner as to draw the ironing belt into uniform pressure engagement with the goods as they are carried along the ironing surface of the chest.

Another object of the invention is to provide efficient means for attaining uniform distribution of sub-atmospheric pressure without danger of "highlighting" or glossing the goods to be ironed and which will not interfere with the even feed of the goods along the surface of the chest.

Sub-atmospheric pressure is accomplished by suction, which has the further advantage of hastening the removal of moisture from the texture of the material during ironing, thus facilitating the ironing and drying operation. We are aware that suction has heretofore been employed for extracting moisture from fabrics, and also that suction exerted directly upon the goods, without the use of an impervious ironing belt, has been suggested as a means for creating ironing pressure. It should be pointed out, however, that all attempts to embody such suggestion in a flat

work ironer have proved impractical and inefficient and, because of variations in thickness and density of materials to be ironed and for other reasons, have been incapable of attaining that important uniform ironing pressure necessary for doing satisfactory work. One of the reasons such attempts to iron by suction without the use of an ironing belt have proved to be impractical will be better understood if one considers what is meant by "ironing." In the laundry art the process of "ironing" consists in the application of heat and pressure to a sufficiently moistened fabric in such a way as to lay the pile of the fabric uniformly in one direction and thus obtain a uniform finish. Thus it is necessary not only to apply both heat and pressure but to do this so that the pressure upon the moistened pile of the fabric lays the pile all in one direction and holds it down while the moisture is removed and the fabric dried to the extent that the set pile will not raise again after the removal of pressure. This is best accomplished by moving the fabric relatively to the hot ironing surface uniformly in one direction.

25 Other objects will be in part obvious or in part pointed out hereinafter.

The invention accordingly consists in the features of construction, combinations of elements and arrangement of parts as will be exemplified in 30 the structure to be hereinafter described, and the scope of the application of which will be indicated in the following claims.

In the accompanying drawings, in which is shown one of various possible embodiments of the 35 mechanical features of this invention—

Fig. 1 is a perspective view of a flat work ironer embodying the present invention;

Fig. 2 is a top plan view of the steam chest in its preferred form;

40 Fig. 3 is a side elevation of the steam chest;

Fig. 4 is a bottom plan view of the same;

Fig. 5 is a transverse section on line 5—5 of Fig. 2;

45 Fig. 6 is in part a longitudinal section on line 6A—6A of Fig. 2, and in part a longitudinal section on line 6B—6B of Fig. 2;

Fig. 7 is a fragmentary section taken on line 7—7 of Fig. 6; and

50 Figs. 8 and 9 are, respectively, enlarged detail sections taken on lines 8—8 and 9—9 of Fig. 2.

Similar reference characters refer to similar parts throughout the various views of the drawings.

55 Referring to the drawings, applicants' flat work ironer will be seen to comprise essentially a steam chest 1, an endless ironing belt 2, an idler pulley 3, a drive pulley 4, and a tensioning pulley 5. The steam chest 1 is suitably supported by means of integrally formed feet 7 resting upon

structural members 9 of a frame, in large part omitted from the drawings, but designed to form a complete supporting structure for all the elements of the ironer. The steam chest may be made of cast iron, cast aluminum, or any suitable steel, and provided with a perfectly smooth and highly polished top or ironing surface 11. This steam chest may be of any suitable width and length to meet the demands for speed in ironing and to withstand ironing pressure. The steam chest is designed to be heated by live steam for the purpose of heating the ironing surface, and to this end is provided with suitable steam passages which, when supplied with live steam, will insure such heating of the ironing surface.

Referring to Figs. 3, 4, 5 and 6, steam inlet openings 12 and 13 are shown entering the steam chest through its bottom wall at opposite ends thereof. Steam entering the hollow chest from these openings passes, as indicated by the arrows in Fig. 7, back and forth through interior connected passages 15 extending substantially the entire width of the chest to impart heat evenly to the ironing surface, the two steam streams meeting at substantially the longitudinal center of the chest to be discharged through an opening 14, also provided in the bottom wall. Any water or condensation collecting within the steam chest will be discharged through the latter opening 14, and it will be noticed, by reference to Fig. 3, that the bottom wall of the steam chest declines from the two ends of the steam chest to the longitudinal center thereof in order to facilitate this discharge of condensate.

Spaced between each adjacent pair of transversely extending steam passages are provided, within the casting of the steam chest, vacuum passages 16. These likewise run crosswise from side to side the full width of the chest and are distributed in alternation with the steam passages 15 practically the full length of the steam chest. These vacuum passages are all connected centrally with respect to the longitudinal center line of the steam chest to a main vacuum chamber 17 extending substantially the full length of the steam chest and opening downwardly through the bottom of the chest. This provides a means by which a pipe or conduit 30, leading to a suitable suction device, such as an air pump 31, adapted to maintain a suitable degree of vacuum or sub-atmospheric pressure within the various vacuum passages, may be connected to the chest.

By reference to Fig. 2, it will be seen that the upper wall of the steam chest is provided throughout its ironing surface with a system or network of crisscross grooves 18 and 19 (shown diagrammatically in Fig. 2 and in detail in Figs. 3 and 9) which cut into the ironing surface. These grooves cover the whole surface save for the short space at the front of the ironer and a lesser distance at the rear thereof. Small perforations 20 drilled through the top wall of the chest connect this network of grooves to the vacuum passages 16 so that, when sub-atmospheric pressure is established in the main vacuum chamber 17 and passages 16, any atmospheric air which passes the belt 2 will be sucked through the holes into the chest.

While the purposes of the present invention may be attained with various arrangements of the crisscross grooving, we preferably cut one set of grooves, such as grooves 18, at an angle of 59° with the transverse axis of the ironing sur-

face of the steam chest, and the other set of grooves 19 at an angle of 61° with said axis of the chest. The reason for this special disposition of grooves will be referred to and explained hereinafter.

Referring to Fig. 1, it will be seen that the belt 2 is supported directly above the steam chest. This ironing belt may consist of an asbestos composition, substantially impervious to air, and pliable and resilient enough to pass readily around the pulleys and press evenly upon the surface of the steam chest. Compositions of this nature heretofore used to a limited extent as padding for ironer rolls, when made sufficiently dense and impervious, are suitable for the purposes of the present invention.

The ironing belt 2 passes over the idler pulley 3 and drive pulley 4 and is driven in the direction of the arrow by means of suitable chain and sprocket drive mechanism, indicated generally by the reference number 22. The spindle 23 of the drive pulley 4 is rigidly supported against up and down movement and is held in a position just to permit the lowest surface of the belt 2 to pass to the drive pulley from the plane of the upper surface of the chest along a path in alignment with said plane or bent slightly downwardly therefrom. The pulley 3 is also spaced with respect to the ironing surface of the chest so that the underside of the ironing belt is in slight contact with the surface. Thus the ironing portion of belt 2 just rests upon the chest. Spindle 24 of pulley 3 is provided at each end with guide blocks 25 slidable up and down in guides 26 to permit vertical motion of the spindle 24 and idler pulley 3, but restraining movement of the pulley in a horizontal direction.

Any suitable means may be provided for feeding goods to be ironed to the ironing surface of the steam chest. In Fig. 1 there is shown a conventional type of work feeding mechanism comprising a pair of rollers 27, 28 mounted parallel to the feed edge at the front of the steam chest and parallel to the axes of the pulleys 3 and 4, and at such elevation that the top element of roller 28 is approximately in the plane of the steam chest surface. A plurality of continuous ribbons 29, known as "feed ribbons," passes over both rollers. As either of the rollers is rotated by suitable gearing, not shown, but operating in synchronism with the speed of the ironing belt, pieces of work spread upon these ribbons are transported onto the steam chest directly under the belt as it passes around pulley 3. In operation, the belt 2 takes hold of the work, draws it along over the heated chest where it is ironed in its passage, and discharges or frees it at the rear end of the steam chest, and machine.

If, under these conditions, we consider that a partial vacuum (sub-atmospheric pressure) is established within the vacuum chambers of the steam chest, it will be understood that the same pressure condition will obtain also at the underside of the belt and top of the ironing surface of the steam chest due to the many perforations through the upper wall of the steam chest and, because of the crisscross network of grooves, will be uniformly distributed over the entire surface of the chest. Since the ironing belt is of such character as to resist to a great extent the flow of air therethrough, uniform pressure will necessarily be developed between the belt and the chest. This pressure will be directly proportional to the degree of the vacuum in relation to atmospheric pressure. This pressure condition is taken

advantage of in the present invention to accomplish ironing of the goods and may be varied or adjusted, as desired by the operator or as the nature of the goods may demand, by merely opening to a greater extent or closing to a greater degree any suitable valve 32 disposed in the suction line between the steam chest and the above mentioned suction pump.

Since clothes to be ironed usually contain a certain amount of moisture, this moisture must be removed during ironing and this requires the application of heat. Such heat is sufficiently supplied by the live steam which circulates through the steam chest, but, as, in the present instance, moisture is removed under conditions of sub-atmospheric pressure, the operation is greatly facilitated.

While it is entirely practical with many classes of goods to arrange the grooving symmetrically—that is, so that both series of grooves lie at the same angle but slope in opposite directions with respect to the front edge of the steam chest—it has been found that by arranging the two series of grooves at different angles, highlighting or local glossing of the surface of the goods is prevented. This is because the fabric being ironed during its passage along the surface of the steam chest avoids being presented along any one line of travel to a constantly uniform pattern which would repeat the action upon the goods of the points of the lands between grooves. Under such conditions of grooving, a cloth traveling over the chest surface in a line perpendicular to the front of the chest will engage continually an ever changing or shifting groove position, thus avoiding danger of highlighting.

By reference to Figs. 8 and 9, it will be seen that each of the grooves 18 and 19 is in the form of a trough having a vertical front wall 33 and a rear wall 34 which slopes rearwardly from the bottom to the top of the groove. Where grooves having vertical rear walls have been used, it was found that the movement of the goods across the grooves set up a slight scraping action between the goods and the rear edges of the grooves, with the result that more than a normal amount of lint was removed from the goods during ironing. This undesirable result is eliminated by forming the grooves as described, and it has been found that not only is the undue formation of lint prevented but also that fabrics passing over such grooves tend to carry away with them such lint as is normally produced, thus preventing clogging of the grooves and chest perforations.

It has been shown by actual practice that, by crisscross grooving the surface of the chest, the pressure or vacuum influence is perfectly uniform over the entire surface area.

In some instances it has been found advantageous to employ a steam chest presenting to the ironing belt an ironing surface convex in the direction of travel of the belt, and it is within the scope of the present invention to cover such a construction.

As many embodiments might be made of the above invention, and as many changes might be made in the embodiment above described, it is to be understood that all structure hereinbefore described as shown in the accompanying drawings is to be considered as illustrative only and not in a limiting sense.

We claim:

1. A flat work ironer including in combination a steam chest having an ironing surface, a substantially air impervious driven friction belt for moving goods to be ironed along said ironing surface, means providing a vacuum chamber within said chest, said chest having a plurality of perforations arranged according to a predetermined pattern throughout a major portion of the contact area of said ironing surface and extending from said chamber through said ironing surface, suction means communicating with said vacuum chamber, and means comprising two groups of parallel grooves formed in said ironing surface and obliquely disposed with respect to the longitudinal axis of said ironing surface, the grooves of one group intersecting the grooves of the other group and each groove intersecting at least one of said plurality of perforations, whereby by the effect of said suction means is distributed uniformly throughout said portion of said contact area to draw said belt down upon the moving goods with substantially uniform pressure at all points of contact.
2. A stationary ironing member for a flat work ironer comprising, an ironing plate having an ironing surface, a suction chamber behind said surface, a network of grooves formed in said surface comprising one plurality of equally spaced parallel grooves all angularly disposed with respect to the transverse axis of said surface and another plurality of equally spaced parallel grooves all angularly disposed with respect to said transverse axis and intersecting said one plurality of grooves, and means connecting said suction chamber with the surface of said plate comprising a plurality of perforations arranged in a plurality of lines extending transversely with respect to said ironing surface, the perforations forming each line being equal in number and spacing with the transversely aligned points of intersection of said intersecting grooves and the perforations of each line being in intersecting relationship with the grooves of at least one of said pluralities of grooves.
3. A stationary ironing member for a flat work ironer comprising, an ironing plate having a perforated ironing surface, a suction chamber behind said perforated surface, and a network of two sets of grooves in said ironing surface communicating with said perforations for distributing the suction effect at said perforations uniformly over the entire ironing surface, said network comprising one plurality of grooves all disposed at one certain angle with respect to the transverse axis of said surface and another plurality of grooves intersecting said one plurality of grooves and all disposed at a different angle with respect to said transverse axis, whereby the points of intersection of successive grooves of the two sets of grooves lie in lines obliquely disposed with respect to said transverse axis.
4. A flat work ironer as in claim 1 in which certain of said perforations lying in transversely extending lines with respect to said axis intersect said grooves at transversely aligned intersections of said grooves and others of said perforations are transversely aligned in parallel with said transversely aligned groove intersections and intersect the grooves of one only of said two groups.

HENRY C. A. MEYER.
